UNITED STATES PATENT OFFICE.

ANTHONY DIXON BROGAN AND ANDREW MURRAY MALLOCH, OF FIRHILL,
GLASGOW, COUNTY OF LANARK, SCOTLAND.

DESIGN FOR THE SURFACE ORNAMENTATION OF GLASS.

SPECIFICATION forming part of Design No. 18,894, dated February 5, 1889.

Application filed November 23, 1888. Serial No. 291,683. Term of patent 14 years.

To all whom it may concern:

Be it known that we, ANTHONY DIXON BROGAN and ANDREW MURRAY MALLOCH, citizens of the United Kingdom of Great

5 Britain and Ireland, residing at Firhill, Glasgow, in the county of Lanark, Scotland, have invented a new and original Design for the Surface Ornamentation of Glass, of which the following is a specification, reference being had

10 to the accompanying drawings, forming part thereof, in which—

Figure I is a face view of our design; and Fig. II is a section on the line II II, Fig. I.

The design is for the surface ornamentation of glass; and, as represented in the drawings, it consists of a series of panels, squares, or quadrilateral figures formed by ridges 1 and bounded by grooves or lines 2, running diagonally or at right angles to each other

20 across the surface of the glass. Disposed symmetrically within and in proximity to the

ridges 1 are a series of small pyramids, 3, and grouped symmetrically around the center of each figure are a number of larger pyramids, 4.

The black lines in the drawings represent the sides of the ridges and figures which are assumed to be in shadow, and the white lines the sides assumed to be struck by light.

We claim—

30 The design for the surface ornamentation of glass, substantially as herein shown and described.

In witness whereof we have hereunto set our hands this 2d day of October, 1888.

A. D. BROGAN.

A. M. MALLOCH.
